(57) **CLAIM**

The ornamental design for a portable cervical traction device, as shown and described.

DESCRIPTION

FIG. 1 is a perspective view of a portable cervical traction device showing my new design;

FIG. 2 is second perspective view thereof;

FIG. 3 is third perspective view thereof;

FIG. 4 is fourth perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.
